AGITATOR FOR WASHING MACHINES

Jabez Curry Nelson, Syracuse, N. Y., assignor to
 Easy Washing Machine Corporation, Syracuse,
 N. Y., a corporation of Delaware

Application October 28, 1935, Serial No. 47,161

2 Claims. (Cl. 68—133)

My invention relates to washing machines and more particularly to a novel agitator or dolly therefor.

An object of my invention is to provide an agitator for a washing machine which may be manufactured at a reasonable cost and which is adapted to cleanse the clothes thoroughly in a minimum length of time without causing undue deterioration of the clothes.

Another object of my invention is to provide an agitator for a washing machine especially adapted to wash delicate fabrics without causing deterioration thereof.

My invention further contemplates the provision of an agitator adapted to be mounted in a vat which comprises a disk and a plurality of columns rising vertically from the disk, the columns presenting a rounded surface to the clothes during operation of the agitator, whereby contact by the clothes with sharp surfaces is avoided.

Another object of my invention is the provision of a novel agitator for a washing machine which is adapted to cause thorough and complete circulation of the clothes around the vat in one circulatory direction so as to continually present new clothes surfaces to the action of the agitator, whereby during the washing operation the entire body of the clothes is subjected to the scrubbing and thread-deforming effect of the agitator.

A further object of my invention is to provide an agitator capable of agitating the clothes and washing fluid with the same effectiveness throughout the depth of cleansing fluid and to provide an agitator which will not tangle the clothes.

Other objects and advantages of my invention will be more apparent from the following description when taken in connection with the accompanying drawing, in which:

Figure 1 is a view of the agitator, partly in section, showing the agitator mounted in a washing vat.

Figure 2 is a view taken on the line 2—2 of Figure 1.

Figure 3 is a view of a modified form of the agitator shown in Figure 1.

Figure 4 is a view taken on the line 4—4 of Figure 3.

The agitator of my invention is adapted to be mounted in a vat or tub 11 in which the clothes and washing fluid are placed. The washing vat may be of any desired shape, either square or, as shown in the drawing, circular in cross section. The agitator, generally indicated by the numeral 12, is preferably mounted centrally of the vat 11

and is driven by a shaft 13 extending upwardly through the bottom of the vat. The shaft 13 may be either rotated or oscillated by any suitable mechanism and from any suitable source of power, not necessary to be shown or described herein, since such driving mechanism is well known in the art to which this invention applies. Preferably, the shaft is driven in an oscillatory manner so as to drive the agitator through an arc of 180°, more or less, and at a speed of between 5 fifty and sixty oscillations per minute.

The upper end of the shaft 13 is splined, as indicated at 14, to receive cooperating splines 15 formed in a collar 16. The collar 16 is press fitted into a sleeve 17 which surrounds the shaft and extends to the bottom of the agitator. The agitator 12 comprises a disk-shaped base 18 which may be made flat or, preferably, have its central portion, as indicated at 19, slightly raised in order to accommodate between the bottom of the base 10 and the bottom of the vat packing or other means for preventing leakage of cleansing fluid around the shaft. The raised portion 19 of the base, as shown in the drawing, merges smoothly into the central vertical sleeve 17 so that the base and 15 central sleeve are integral.

Rising vertically from the base 18 are, preferably, three circular blades or vertical columns 21 which are spaced about the central sleeve 17. Preferably, the vertical columns 21 are placed 20 upon the disk so that the outer vertical edges thereof substantially coincide with the outer edge of the disk. The vertical columns are also preferably somewhat smaller in diameter than the radius of the disk so that an open space 25 exists around the central sleeve 17.

A cap 22, of any desired shape, is placed upon the top of the agitator and retained in position by a screw 24 threaded into the top of the sleeve 17. The cap 22 has a bottom horizontal surface 26 having an opening 27 for the reception of the sleeve. A plate 26', secured to and extending over the tops of the columns, serves as a closure for the columns and prevents splashing of the liquid upwardly. The plate 26' 45 may be secured to the sleeve 17 and to the columns in any suitable manner as by welding or may be formed integral therewith.

When the agitator is oscillated, the clothes are carried backwardly and forwardly in the 50 vat in accordance with the oscillations of the agitator. Because the columns present rounded surfaces to the clothes which are effective throughout the depth of the liquid in the vat, the clothes, while vigorously agitated by the agi- 55

tator, are not subjected to the action of sharp surfaces so that little deterioration of the clothes results. At times, during the oscillation of the agitator, articles of clothing are caught in the 5 openings between the columns and between the central sleeve and the columns and, through several oscillations, are carried back and forth with the agitator and subjected to a whip-lash action which serves to deform the threads and 10 dislodge the dirt from the clothes.

In Figures 3 and 4, I have shown a modified form of the structure shown in Figure 1 which while essentially the same in construction, has a very different action on the clothes due to the 15 fact that the columns are cut in half so as to provide semi-circular columns extending from the base 18 to the top of the agitator. The semi-circular columns are mounted symmetrically around the central sleeve 17 with the open portions 20 27 of the columns all facing in the same direction and with the vertical edges 28 and 29 preferably in the same vertical plane as the axis of the agitator.

With this construction, when the agitator is 25 rotated in a clockwise direction, the semi-circular columns, because of the cup-shaped formation, exert a positive, powerful thrust on the clothes in the clockwise direction. When the agitator is reversed, because the rounded surfaces 30 30 of the cups are presented to the clothes, the agitator more or less slips through the water without exerting any material tendency to reverse the direction of rotation of the contents of the vat. The clothes are thus caused to continuously circulate around the vat in one 35 circulatory direction. While the action of the agitator, shown in Figures 3 and 4, is harsher on the clothes than that shown in Figures 1 and 2, the tendency of the cups to exert any deleterious 40 effect on the clothes is minimized by rounding off the vertical edges 28 and 29 of each of the hemispherical columns. The agitator of Figures 3 and 4, because the clothes are sometimes

caught in the cups as well as caught between adjacent columns, are at times carried back and forth with the agitator, whereby a substantial whip-lash action occurs upon reversal of the agitator which results in thread deformation 5 and a loosening of the dirt lodged in the clothes.

It will be apparent from the foregoing description that the agitators of my invention are of new and novel design and that various changes and modifications may be made in the 10 form and relation of parts without departing from the spirit of the appended claims.

I claim:

1. In a washing machine, a washing vat adapted to contain a quantity of clothes and 15 washing fluid and having an approximately normal surface level of washing fluid, an agitator mounted in said vat, means for oscillating said agitator, said agitator comprising a central axis, a base, and a plurality of columns, each of said 20 columns being semi-circular in cross section and extending upwardly from said base, the open portions of said columns facing in the same circular direction and with the back of one column facing circularly around the base upon 25 the open portion of an adjacent column.

2. An agitator for washing machines adapted to be mounted in a vat containing clothes and washing fluid, said agitator comprising a base substantially smaller in diameter than the 30 diameter of the vat, a central post extending upward from the base, and a plurality of columns, each of said columns being semi-circular in cross section and extending upward from the base rigid therewith and spaced around the central post, said columns being of a diameter substantially half the radius of the base and having their open portions facing in the same circular direction and with the back of one column facing circularly around the base upon the open 35 portion of an adjacent column.

JABEZ CURRY NELSON.
